UNITED STATES PATENT OFFICE.

ERASTUS E. WINKLEY, OF LYNN, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

SORTING-MACHINE.

1,286,471.

Specification of Letters Patent.

Patented Dec. 3, 1918.

Application filed June 12, 1916. Serial No. 103,158.

To all whom it may concern:

Be it known that I, ERASTUS E. WINKLEY, a citizen of the United States, residing at Lynn, in the county of Essex and State of Massachusetts, have invented certain new and useful Improvements in Sorting-Machines; and I do hereby declare the following to be a full, clear, and exact description of the invention, such as will enable others skilled in the art to which it appertains to make and use the same.

This invention relates to a machine for automatically sorting articles of a generally uniform character, so as to separate them into groups according to their variations in form. The invention is particularly applicable to the operation of sorting pieces of shoe-stock, such as heel-lifts, in accordance with the form of their marginal or peripheral portions, and so as to separate those which have imperfections in the form of the outline, from those which conform to a given standard. The invention is also applicable, however, to the sorting of various other articles.

The general object of the invention is to produce a machine which will automatically present the heel-lifts, or other articles which are to be operated on, one-by-one to a detecting mechanism which is adapted to test the surface of the article, and which will thereafter discharge the article at one point or another according to the characteristics in the form or contour of the surface tested by the detecting mechanism. A more particular object of the invention is to produce a machine in which heel-lifts or similar articles may be introduced in the form of a stack, and in which the lifts, after they have been acted upon by the machine, shall be discharged still in a stacked relation, for convenience in handling the articles preparatory to subsequent operation upon them. A still further object of the invention is to produce a machine of which the detecting mechanism may be quickly and conveniently adjusted for the form and size of the articles upon which it is to operate.

To the foregoing ends the invention consists in the machine hereinafter described, as it is defined in the following claims.

In the accompanying drawings Figure 1 is a front-elevation of a machine embodying the present invention; Fig. 2 is a partial

front-elevation, showing the machine in the same aspect as in Fig. 1 but on a larger scale, and with parts broken away to show the interior mechanism; Fig. 3 is a vertical section substantially on the line 3—3 in Fig. 1, but on a larger scale than the latter figure; Fig. 4 is a vertical section of a detail of the machine, on the line 4—4 in Fig. 3 but on a larger scale than the latter figure; Fig. 5 is a vertical section of the transferring mechanism, on the line 5—5 in Fig. 2 but on a larger scale than the latter figure; Figs. 5^a and 5^b are detail plan-views of portions of the picker-mechanism, Fig. 5^b being partly in section; Fig. 6 is a front-elevation of the detecting-mechanism with a part broken away; Fig. 7 is a section on the line 7—7 in Fig. 1, but on a larger scale than the latter figure; Fig. 8 is a perspective view showing, in detail, the cooperation between one of the detectors and the templet and a heel-lift; Fig. 9 is a vertical axial section of the detecting-mechanism, similar to the right-hand upper portion of Fig. 3 but on a larger scale and with the parts in different position; Fig. 10 is an elevation, partly in section on the line 10—10 in Fig. 2, showing in end-view the lift-feeding mechanism; Fig. 11 is a plan-view of the machine, with parts broken away; Fig. 12 is a partial horizontal axial section of the detecting-mechanism; and Figs. 13 and 14 are horizontal sections, on the line 13—14 in Fig. 3 but on a larger scale than the latter figure, and showing the parts in two different positions.

The invention is illustrated as embodied in a machine adapted for sorting heel-lifts so as to separate from the perfect lifts those which are imperfect in their edge portions. In dieing-out heel-lifts it sometimes happens, from imperfect machine operation and carelessness on the part of the operator, that the die cuts partly into a space in the leather from which a lift has already been cut, so that there is a concavity in the edge of the lift so formed. The present machine is adapted to test the outline of a lift and detect imperfections of this character, and also imperfections which may result from holes or flaws in the leather which happen to be located at the edges of the lifts. The machine is also adapted to detect the presence of a lift larger than the predetermined size, or having any projection beyond the

predetermined outline from which the machine is adjusted.

The machine is designed to hold a lift 20 in the vertical plane of operation of a set of 5 radially movable detectors which may conveniently be termed "feelers", these feelers having the form of sliding bars 22 which are supported and guided radially upon a circular plate 24, being retained in the guide- 10 ways by a removable plate 26, all as shown in Figs. 3 and 9. When the heel-lift is in position for operation, as shown in Fig. 9, the feelers are automatically moved inwardly, until operative projections 30 on 15 their inner ends are brought into engagement with the edge of the lift at closely adjacent points throughout its periphery. A templet or pattern 28, (Fig. 8) corresponding to the required form of the lift but 20 somewhat larger in scale, is then moved horizontally toward the inner ends of the feelers. Each feeler is provided, at its inner end, with a rearward projection 27, and the templet is provided with a slot 29 which 25 is adapted to receive all of the projections 27 when the feelers are in engagement with a lift of normal form. When such is the case the templet performs a movement of predetermined range, and the heel-lift is 30 then discharged by mechanism controlled by the templet, this mechanism being arranged to discharge the lift, under such circumstances, on a table provided for holding a stack of perfect lifts. If, on the other hand, 35 the normal movement of the templet above described is prevented, by engagement of the surface of the templet with the projection 27 on any one of the feelers, this indicates that the feeler has either entered a concavity 40 or imperfection on the edge of the heel-lift, which has permitted it to move inwardly beyond its normal position of engagement with the lift, or else has engaged a part of the lift which extends beyond the normal 45 predetermined outline. The mechanism by which the lift is supported and transferred then operates automatically to discharge the imperfect lift upon a second table, provided for such lifts, thereby separating it from the 50 perfect lifts.

The use of a large number of feelers, engaging the lift simultaneously at closely adjacent points on its surface, while not essential, is a valuable feature of the illustrated machine, since it causes the entire periphery of the lift to be felt or tested at once, thus reducing to a minimum the time required for the feeling operation. The arrangement of the feelers to engage only the edge or periphery of the lift adapts the illustrated machine to detect only variations in the diameter or imperfections in the marginal portion of the lift, but for the particular purpose in question, namely the sorting of heel lifts, this is sufficient, since it is par-

ticularly in its edge that the lift should be free from imperfections, this being the only part of the lift which is visible in the finished heel. It will be apparent, however, that in the case of articles which must be free of imperfections at points other than the marginal portion, the machine, by a mere extension of the mode of operation herein described, may be provided with feelers adapted to engage such other portions of the articles to be sorted.

The various mechanisms by which the above described operations are carried out will now be described, beginning with the transferring mechanism by which the heel-lift is held and is presented to the feeler-mechanism, and then discharged at the proper point.

The frame of the machine comprises a central hollow column 32, and at the upper 85 part of this column a shaft 34 is mounted to rotate in vertical position. This shaft carries, at its upper end, a casting comprising four hollow radial arms 36, each of which arms is provided with what may be described as a "picker", comprising a shank 38 which moves within the arm. The picker is adapted to seize a heel-lift, in the manner hereinafter described, by engagement with one of its lateral surfaces, and to hold the lift firmly in the position in which it is seized.

Extending from the upper part of the column 32 are four brackets, supporting tables 40, 42, 44 and 46 which radiate in the 100 form of a cross from the column, as shown in Fig. 11. The table 40 is the feed-table, upon which is supported a stack of the lifts to be operated upon. The table 42 supports the feeler-mechanism; the table 44 receives 105 and supports, in a stack, the perfect lifts as they are discharged by the transferring-mechanism; while the table 46 receives the imperfect lifts from the transferring-mechanism.

The four pickers of the transferring-mechanism are arranged to come to rest simultaneously in co-operative relation with instrumentalities, supported by the four tables, and then to revolve through a space 115 of 90° and again come to rest, so that each picker moves from the feed-table to the feeler-mechanism, and thence to the two receiving-tables in order, and finally to the feed-table again. For this purpose the shaft 34 120 is mounted to rotate in upper and lower bearings 48 and 50 supported by the column 32, as shown in Figs. 3 and 5. The shaft is given its intermittent one-quarter rotations by mechanism shown particularly in Figs. 3 and 4. A gear 52 is fixed on the lower end of the shaft, and alongside this gear a rod 54 is fixed in horizontal position on the column. Upon this rod is mounted a yoke-shaped rocking member comprising a con-

cavo-convex" semi-cylindrical bar 56, which is co-axial with the rod 54, and has heads 58, at its ends, which are bored to receive, and have bearings upon, the rod 54. The rocker 5 is restrained against longitudinal movement by engagement of its ends with bosses on the column, as shown in dotted lines in Fig. 3. The rocker is provided with locking-teeth 60 at its central portion, these teeth being 10 adapted to coöperate with the teeth of the gear 52 so as to lock the gear and the shaft 34 against rotation. The parts are shown in locked position in Fig. 4, but by a movement of the rocker in the direction of the arrow in Fig. 4, the teeth 60 may be disengaged from the gear 52 when the latter is to be partially rotated.

To produce the rocking movement above described an arm 62 depends from the right-hand end 58 of the rocker and is connected, by a link 64, with the upper end of a cam-lever 66 which is pivotally mounted on the inside of the column 32. This lever carries, at its lower end, a roller 68 which engages 25 a cam 70 mounted on a power-shaft 72. This shaft, as shown particularly in Fig. 2, is journaled on the column 32 and is provided with fast and loose pulleys 74 and 76, through which it may be connected with a 30 suitable source of power. The cam produces the locking movement of the rocker positively, while movement in the opposite direction is produced by a spring 71 attached to the cam-lever 66.

The rotative movements of the gear 52 are produced by a slide 76 which is mounted to move upon the rod 54 within the space spanned by the rocker. This slide has rack-teeth 78 adapted to coöperate with the gear 52. The slide 76 has longitudinal shoulders 40 engaged by the edges of the bar 56 of the rocker, as shown in Fig. 4, so that the slide participates in the rocking movement, and thus its teeth 78 are brought into and out 45 of engagement with the gear 52 alternately with the teeth 60 of the rocker.

The sliding movements of the slide 76 are produced by cam-mechanism. For this purpose the slide is provided with two lugs 50 80, which embrace the upper end of a bell-crank cam-lever 82 which is pivoted on the frame of the machine. The lever 82 carries a roller 84 which engages a cam 86 on the power-shaft 72. The cam produces movement of the slide positively in the operative direction, while the idle return movement is produced by a spring 88 attached to the lever 82.

The construction of the pickers is shown 60 particularly in Fig. 5. Each shank 38 moves freely within the bore of one of the arms 36, and a sleeve 90 is arranged to slide between the shank and the arm. A spring 92, coiled around the shank and interposed between the sleeve 90 and the enlarged head

of the shank, tends to hold the sleeve 90 at the rear end of the shank, in engagement with a cap 93 screwed thereon. The sleeve 90 has a portion which projects downwardly into a horizontal slot in the bottom 70 of the arm 36, and upon this portion a roller 94 is mounted. By means of this roller sliding movements are imparted to the sleeve 90 and the shank, by mechanism hereinafter described.

The picker is provided, at its outer end, with claws 96 pivotally mounted in radial slots in the shank. Each claw is provided with a sharp hook-shaped prong 98 which may be caused to move outwardly beyond the end of the shank when the claw is rocked upon its pivot, in such manner that the several claws will pierce and hold the substance of the heel-lift with which the picker may be engaged.

The claws are actuated by the engagement, with notches in the claws, of a flange 100 on the outer end of a rod 102 which slides axially in the shank. The inner end of the rod is attached to a head 104, which slides in 90 a central bore in the shank. The inner end of the bore is occupied by what may be described as the "latch-slide" 106. Upon a transverse pivot-pin 108 in the latch-slide a hook 110 and a latch 116 are mounted. 95 The hook is provided with a finger 112 adapted to engage the cap 93 when the latch-slide is in its innermost position. A spring 114, interposed between the latch-slide and the head 104, and a spring 120 interposed 100 between the head 104 and the head of the shank 38, tend to hold the latch-slide in its innermost position, and in this position of the parts the finger 112 tends to swing the hook 110 upwardly through a slot 121 in 105 the shank, so as to cause its beveled end to engage in an opening 122 in the sleeve 90. A spring 118 tends to throw the latch 116 upwardly, but in the rearmost position of the latch-slide the latch is held in depressed 110 position by engagement with the wall of the shank, as shown in Fig. 5.

The mechanism above described operates as follows: Suppose that the picker is in a position of presentation to a heel-lift which is firmly supported in vertical position by the feed-mechanism, and that the roller 94 is then moved outwardly, that is, in the direction of the heel-lift. The movement of the sleeve 90 is transferred to the shank 38 115 through the spring 92, and the shank accordingly moves into engagement with the heel-lift, the parts within the shank suffering no change of position until this engagement occurs. As soon as the shank is seated 120 against the lift and its movement is thereby arrested, the continued movement of the slide 90 causes compression of the spring 92. This movement is also transferred, through the hook 110, to the latch-slide 106, which 130

thereupon moves outwardly in the bore of the shank, so as to compress the springs 114 and 120, and since the latter spring is the weaker, this results in an outward movement 5 of the head 104 and the rod 102, whereby the claws are swung outwardly into engagement with the heel-lift. As soon as the claws have become fully embedded in the heel-lift, the movement of the head 104 ceases, and further movement of the latch-slide causes 10 further compression of the spring 114. When the sleeve 90 has nearly reached the limit of the movement imparted to it by the roller 94 the latch 116 has been brought to a position 15 of engagement with the opening 121 in the wall of the shank, and the spring 118 then throws the latch upwardly into this opening. At the same time a part of the opening 122 in the sleeve 90 is directly above the opening 20 121, so that the beveled extremity of the latch enters the opening 122. Upon the return-movement of the roller 94 and the sleeve, the latch-slide is retained in its advanced relation to the shank by the engagement 25 of the latch with the opening 121. The hook is thrown out of operative position, however, by engagement of its beveled end with the wall of the sleeve, and since the finger 112 is not at this time in engagement 30 with the cap 93, the hook remains in depressed position. Owing to the advanced position in which the latch-slide is retained by the latch, the claws 96 continue to hold the heel-lift.

35 After the picker in question has been brought into coöperative relation with the feeler-mechanism it may be again advanced, by the coöperation, with the roller 94, of mechanism for that purpose, and since the heel-lift is not at this time brought into positive engagement with any fixed part, the picker continues to hold the lift during this advancing movement and during the subsequent retreating movement by which the lift 40 is removed from the feeler-mechanism.

When the picker in question has been brought into one or another of the discharging positions it then operates in such a manner as to project the lift into engagement 45 with certain abutments which constitute part of the receiving-mechanism, as hereinafter described, and the arrest of the movement of the heel-lift, which results from this engagement, results also in the release of the lift by the picker. Considering Fig. 5 again, it will be apparent that with the parts in the positions in which they were last described, if the outward movement of the shank 38, produced by the movement of the roller 94, be 50 positively arrested, as by the engagement of the lift with a fixed abutment, a relative movement of the sleeve 90 and the shank will occur. Owing to this movement the sleeve, through the action of its wall upon the beveled upper surface of the extremity of the

latch, causes the latch to swing downwardly until the shoulder, at the inner end of this beveled surface, is brought opposite the beveled left-hand end of the opening 121. Thereupon the springs 114 and 120 at once 70 force the latch-slide inwardly in the shank, to the position of Fig. 5, thereby disengaging the detent from the sleeve 90 and retracting the claws from engagement with the heel-lift. Upon the return-movement of the slide 90 it again moves to its innermost position, thus restoring all the parts to the positions of Fig. 5.

The movements imparted to the pickers through the rollers 94 are produced by the 80 agency of four bell-crank levers 122, 124, 126 and 128, as shown in Figs. 3, 5, 13 and 14. These levers are mounted on pivots 130 supported on a ring 132 constituting a part of the frame of the machine, this ring being mounted at the upper end of the column 32. The levers are located in line with the four tables respectively, and they have bifurcated upper ends into registry with which the rollers 94 are successively brought 85 by the rotation of the shaft 34.

The bell-crank levers are all actuated simultaneously, by engagement of their inner arms with a slotted disk 134 which is integral with a sleeve 136 which slides on the 90 shaft 34. The sleeve is provided with an annular slot 138, which is engaged by a roller 140 on the end of a lever 142, this lever being pivoted on a stud 144 on the frame of the machine. The lever is connected, by a 100 rod 146, with a cam-lever 148, and the cam-lever carries a roller 150 which engages a closed path in a cam 152 on the power-shaft. This cam imparts positive upward and downward movements to the sleeve 136 at 105 suitable times in the operation of the machine, and thus two or more of the pickers are moved radially outwardly and inwardly at the same time.

During the rotary movements of the shaft 110 34 the rollers 94 are out of the control of the bell-crank levers, and their positions and movements are then determined by means shown particularly in Figs. 13 and 14. A plate 154, which is connected, by arms 155, 115 with the frame-ring 132, is provided with a slot 156 extending concentrically with the shaft 34, and in this slot each roller is guided as it moves from the feed-position, shown at the left of Figs. 13 and 14, to the position 120 of presentation to the feeler-mechanism, shown in the upper parts of these figures, the picker being at this time in its retracted position. At the end of the movement in question the roller is brought into engagement 125 with the lever 124, so that by the movement of this lever the picker may be projected and retracted as above described.

During the next quarter-rotation of the shaft 34 the roller 94 in question may follow 130

either of two alternative paths, according as the corresponding picker supports a perfect or an imperfect heel-lift. One of these paths 158 extends outwardly to a position of engagement with the lever 126, while the other path 160 extends inwardly so as to cause the roller to avoid engagement with the lever. The paths 158 and 160 are controlled and partly formed by a gate 162, 10 which is fixed on the upper end of a short rock-shaft 164. This rock-shaft is moved automatically by mechanism hereinafter described.

Assuming that the roller in question moves 15 into coöperation with the lever 126, as above described, its further movement is through a path 168, by which it is directed inwardly so as to avoid engagement with the lever 128. This mode of operation is illustrated in Fig. 20 13. If, however, the roller avoids the lever 126, as shown in Fig. 14, by following the path 160, it then avoids the path 168 and follows a path 166 by which it is brought into engagement with the lever 128, and the 25 picker is thus caused to discharge its lift at this point, which is in alinement with the table 46 for receiving imperfect heel-lifts.

The last quarter-revolution of the shaft 34 carries the roller back to the lever 122, 30 by which it is then moved to cause the corresponding picker to engage a heel-lift held by the feed-mechanism on the table 40.

The selection between the paths 166 and 168 is controlled by a gate 170, which is 35 mounted upon the upper end of a short rock-shaft 172 actuated by mechanism hereinafter described.

The feed-mechanism supported by the table 40 is shown particularly in Figs. 1, 2, 40 10 and 11. The heel-lifts 20 are supported in a stack, resting with their straight breast-edges upon a horizontal rail 174. At either side of this rail two endless conveyer-chains 176 are mounted in horizontal stretches, supported on sprocket-wheels journaled on vertical axes. These chains are provided, at 45 intervals, with angular lugs 178 adapted to engage either the marginal or the lateral edges of the adjacent lifts of the stack as shown in Fig. 11, so as to feed the stack forwardly along the rail 174.

Intermittent movements are given to the chains to feed the stack after the removal of each lift by the transferring-mechanism. 50 For this purpose the sprocket-wheels which support the inner turns of the chains are mounted on vertical shafts 180 provided, at their lower ends, with worm-wheels engaging worms on a shaft 186 journaled transversely on the table 40, as shown in Fig. 2. A rocker-arm 188 swings about one end of the worm-shaft and is coupled with the shaft by a roller-wedged clutch, as shown in dotted lines in Fig. 2. This rocker is connected, by a rod 190, with a lever 192 which

is pivoted on a stud 194 on the frame of the machine. The inner end of the lever is connected, by a rod 196, with a cam-lever 198. This cam-lever carries a roller which engages a cam 200 on the power-shaft 72. The 70 advancing movement of the chains is produced yieldingly by a spring 202 connected with the lever 192, while the idle return-movement of the rocker-arm 188 is produced by the cam. With this arrangement the cam 75 may be designed to impart a movement more than sufficient for the thickness of the thickest lift which may be fed, the spring 202 accommodating itself to the shorter movement actually permitted to the chains. 80

The advancing movement of the stack of lifts produced by the chains is limited by engagement of the innermost lift with stop-arms 204. These arms are mounted to rock on pivots 206, and they are connected, by 85 links 208, with the upper end of a rod 210 which slides vertically in a sleeve 212 mounted on the table 40. A spring 214, interposed between the sleeve and the head 216 on the lower end of the rod, tends to slide the rod 90 downwardly, and thus swing the stop-arms into the operative position shown in Fig. 10. When a lift is to be removed by one of the pickers, however, the stop-arms are swung out of operative position. For this purpose 95 the rod 210 is connected, by a rod 218, with a cam-lever 220. This lever carries a roller 222 which engages a cam 224 on the power-shaft 72, and the cam acts to cause the rod 218 to lift the rod 210 at the proper times 100 in the operation of the machine.

During the engagement of the innermost heel-lift by the picker which seizes it, it is necessary to support this lift firmly against yielding movement which might otherwise 105 be caused by the pressure of the picker against it, and for this purpose several of the innermost heel-lifts in the stack are clamped at this time. The lateral edges of the lifts in question are engaged by clamp-blocks 226, which are mounted on two slides 228, as shown in Fig. 10. These slides have bifurcated upper ends which are guided by a transverse guide-bar 230, while the slides are supported upon and actuated by a transverse screw-shaft 232, which is journaled in bearings on the table 40 and provided with right and left-hand screw-threads engaging corresponding threads in the slides 228. 115

The screw-shaft 232 is rotated in opposite directions to move the clamp-slides first inwardly, to cause them to clamp the heel-lifts, and then outwardly, to relieve the lifts from pressure when they are fed forwardly by the conveyer-chains. For this purpose a 120 pinion 234 is mounted upon the screw-shaft in position to mesh with a gear-segment 238. This gear-segment is journaled on the stud 194 as shown in Figs. 2 and 10, and is connected, by a rod 240, with a cam-lever 242. 130

The cam-lever carries a roller 244 which engages a cam 246 on the power-shaft. A spring 252 attached to the cam-lever causes yieldingly the movement of the parts by which the clamp-slides are moved toward each other to clamp the heel-lifts, while the return-movement is caused positively by the action of the cam.

In order that the range of movement of the clamps may be adjusted in accordance with different sizes of heel-lifts, the pinion 234 is mounted upon the screw-shaft with provision for axial movement by which it may be disengaged from the gear-segment 238. For this purpose the pinion is formed integral with a sleeve 236, which is splined upon the shaft and is provided, at its outer end, with a knurled head 250. A spring 248 is interposed between the pinion and a disk 249 fixed on the end of the shaft, this spring tending to hold the pinion normally in operative position, but being adapted to yield when the knurled pinion is pulled outwardly for the purpose of disengaging the pinion from the gear-segment. When the pinion is disengaged it may be rotated by means of the knurled head.

The feed-mechanism just described is not claimed herein, as it is described and claimed in an application for Letters Patent of the United States, Serial No. 206,784, filed December 12, 1917, on behalf of the present applicant, said application being a division of Letters Patent 1,270,476, granted June 25, 1918 to said applicant. The construction and operation of the feed mechanism are described herein only so far as it is necessary for an understanding of the coöperation of the feed-mechanism with the other parts of the machine.

The feeler-mechanism will now be more particularly described. Each feeler 22 is connected, by a link 254, with an arm 256 of a bell-crank lever, the levers being mounted in slots in a flange extending rearwardly from the periphery of the plate 24, as shown in Fig. 9. The pivots of the bell-crank levers are secured in place by a bearing-ring 258 removably secured to the back of the flange. In Fig. 9 all of the bell-crank levers and parts associated therewith, except those at the section-plane, are omitted for the sake of clearness of illustration.

Each bell-crank lever has an arm 262 which extends radially toward the axis of the feeler-mechanism, and which coöperates with a disk 264. This disk is mounted on a sleeve 268 which slides horizontally on a rod 266. The rod is fixed in an upright 267 on the frame of the machine.

The disk, by its inward movement on the rod, swings the bell-crank levers in a direction to move the feelers outwardly and hold them in their outward positions, while the inward movements of the feelers, by which

they are engaged with the heel-lift, are produced by springs 260 attached to the several lever-arms 256.

The disk 264 is moved by the engagement of its annularly grooved hub 268 with the bifurcated end of the upwardly extending arm of a bell-crank lever 270, this lever being pivoted on a stud 272 on the frame of the machine. The horizontal arm of the lever 270 is connected, by a rod 274, with the horizontal arm of a second bell-crank lever 276, also pivoted on the frame of the machine. The lever 276 is connected, by a rod 280, with a bell-crank cam-lever 282, which is pivoted at 283 on the frame of the machine, and which carries a roller 284 co-operating with a cam 286 on the power-shaft. The cam produces positively a movement by which the disk 264 is engaged with the lever-arms 262 to move the feelers outwardly as shown in Fig. 3, while the opposite movement of the parts is produced yieldingly by a spring 288 connected with the cam-lever 282.

The templet 28 is also arranged to slide upon the rod 266, and it is actuated by connection with the disk 264. For this purpose the slotted hub 290 (Fig. 12) of the templet is articulated with a forked lever 292, which is fixed on a rock-shaft 293. The rock-shaft is journaled in a bracket 294 projecting inwardly from the plate 24. The outer end of the lever is connected with a rod 296, which slides loosely through a hole in the disk 264 and is provided, at its outer end, with adjustable stop-nuts 298. A spring 300 is connected with an arm 302 on the lower end of the rock-shaft.

When the disk 264 is moved inwardly to produce the outward movement of the feelers, the spring 300 rocks the shaft 293 and the lever 292 in a direction to cause an outward or retracting movement of the templet, the parts thus assuming the positions of Fig. 3. After a heel-lift has been brought into position to be acted upon by the feeler-mechanism, however, the disk is retracted as shown in Fig. 9, thus engaging the nuts 298 and pulling the rod 296 outwardly. This causes the lever 292 to swing in a direction to swing the templet inwardly into the space between the ends of the feelers. If, however, the templet engages and is arrested by the projections 27 of one or more of the feelers, as shown in Fig. 9, owing to the fact that a feeler has assumed an abnormally inward or outward position in consequence of a defect in the heel-lift, the stop-nuts 298 arrest the return-movement of the disk 264 before its completion. This fact is taken advantage of to control automatically the discharge of the lift in question by the transfer-mechanism.

To the foregoing end the bell-crank lever 276 is connected, as shown in Figs. 3, 5 and 130,

9, with a rod 304 which slides in a bearing-sleeve 306 on the plate 154. As shown in Figs. 5, 13 and 14, the inner end of the rod 304 coöperates with an arm 308 fixed on the 5 lower end of the rock-shaft 164 which carries the gate 162. If, therefore, the disk 264 completes its full normal movement the corresponding movement of the rod 304 causes the lever 308 and the gate 162 to be 10 swung to the position of Fig. 13, so that the roller 94 of the picker which is at this time in coöperation with the feeler-mechanism will be thereafter guided into engagement with the lever 126, to cause the lift to 15 be discharged on the table 44. If, however, the disk 264 does not perform its normal outward movement the gate is not moved as described, but remains in the position of Fig. 14. The gate is always brought to this 20 latter position after the passage of a preceding roller through the path 158, by the engagement of the roller with the heel 310 of the gate, in a manner which will be apparent from Figs. 13 and 14, and the gate 25 remains in this position of Fig. 14 unless moved by the action of the rod 304 as above described.

In the case of an imperfect lift the roller 94 passes through the path 160 as before described, and it is then directed into the path 166 by the gate 170. The proper position of the gate 170 is produced by the action of an arm 312 which is arranged to form a part of either the path 158 or the path 160, according to circumstances. This arm is fixed 30 on the upper arm of a rock-shaft 314, which carries at its lower end an arm 316. The arm 316 is connected, by a link 318, with an arm 320 on the lower end of the rock-shaft 40 172. If the roller 94 traverses the path 160 it swings the arm 312 to the position shown in Fig. 14 and by this movement the gate 170 is swung, through the connections just described, to the position in Fig. 14, in 45 which it directs the roller into the path 166. The roller then engages the lever 128, and the heel-lift is discharged by the picker upon the table 46. If, on the other hand, the roller 94 has previously traversed the 50 path 158, the arm 312 is thus swung to the position shown in Fig. 13, and the gate 170 is thereby moved to the position shown in that figure, thus causing the roller to follow the path 168.

The mechanism by which the lifts are received and held in a stack upon the table 44 is shown particularly in Figs. 2, 7 and 11. Above the table is a horizontal rail 322 upon which the breast-edges of the heel-lifts rest, 60 and in order that this rail may be adjusted in height, in accordance with the different sizes of the heel-lifts which are to be operated upon, it is supported upon stems 324 which slide vertically through the table. 65 These stems are connected, by pins 326 at

their lower ends, with arms 328 fixed on a rock-shaft 330 which is journaled below the table. At the outer end of the rock-shaft is fixed an arm 332 (Fig. 1) provided with a set-screw 334 which passes through a slot 70 in the flanged end of the table, so that the arm may be swung upwardly or downwardly and then fixed in adjusted position by turning the screw. A similar arrangement, used in connection with the table 46, is more fully 75 illustrated in Fig. 2. On the top of the table 44 are mounted two castings 336 which are provided with base-flanges 338. These flanges are fixed adjustably to the surface of the table by means of set-screws 340 passing 80 through slots in the flanges, so that the castings may be adjusted toward and from each other. At its inner end each casting is provided with two arms 341 and 342, which support a vertical pivot 344. The heel-lifts 85 are confined laterally by arms 346 in the form of strips of resilient sheet-metal, these arms being mounted on the pivots 344. Compression-springs, inclosed within housings 348 on the arms 341, bear against the arms 346 near 90 their pivotal points and tend to swing the arms toward each other, so as to cause them to press against and frictionally retain the heel-lifts. The castings 336 are adjusted at such a distance that the heel-lifts will enter 95 readily between the pivoted forward ends of the arms 346, and means are provided for making this adjustment simultaneously and to an equal extent upon both of the castings. For this purpose bell-crank levers 352 are 100 employed, these levers being mounted upon parallel rock-shafts 354 journaled below the table 44. The upright arms of the bell-crank levers engage openings in the base-flanges 338, as shown in Fig. 7, while the other arms 105 of the levers are articulated together by segmental gears.

In order that the table 44 may support a long stack of heel-lifts, an additional pair of spring-arms 350 is pivoted at the rear extremities of the castings 336, as shown in Fig. 1, these arms being also swung toward each other by springs in the same manner as in the case of the arms 346.

To provide for the automatic release of 115 the heel-lift by the picker when the picker is projected, in the manner hereinbefore described, toward the table 44, it is necessary, as has been stated, that the heel-lift be pressed by the picker against an unyielding surface. For this purpose, and also for the purpose of forcing each lift automatically into engagement with the preceding lifts and retaining the lifts at the inner end of the stack, the machine is provided with helical 120 members 358 which are mounted, on short shafts 360 journaled in a support at the inner end of the table 44, in such positions that these members overlap the end of the stack of lifts, as shown in Fig. 7. These 12

helical members rotate constantly, and the lift is first pressed against them by the picker and then, by their rotation, the lateral edges of the lift are drawn rearwardly and the lift is forced into engagement with those previously introduced into the stack.

The shafts 360 are connected, by bevel-gears 364, with vertical shafts 366. These vertical shafts are connected together, in turn, by skew-gears and a horizontal shaft 367, as shown in dotted lines in Fig. 7. One of the shafts 366 is also connected, by bevel gears 368, with a horizontal shaft 370. The shaft 370 is geared to one of two vertical shafts 371 which are analogous, in connection with the table 46, to the shafts 366 at the table 44. The shafts 371 are also connected by gears and a horizontal shaft 372, shown in dotted lines in Fig. 11, and the shaft 372 is provided with a sprocket-wheel 374 which is connected, by a chain 376, with a sprocket-wheel on the power-shaft 72, so that the helical members at both the tables 44 and 46 are rotated constantly.

28 The devices for holding the heel-lifts on the table 46 are, in general, similar to those at the table 44. Owing, however, to the fact that it is necessary to provide for fewer heel-lifts on the table 46, the castings 378, by 30 which the lift-retaining arms are supported, are connected pivotally with the table at their outer ends, by means of studs 380, and are adjusted by swinging them about these studs. To coördinate the adjusting movements of the two castings they are connected together by gear-segments 382 located below the table 46. The height of the supporting-rail 384 is regulated by mechanism controlled by a set-screw 386 corresponding in 40 function to the screw 334 on the table 44.

While the invention has been described particularly as embodied in a machine for sorting heel-lifts, it will be apparent that it is adapted for various other purposes, and 45 that it may be embodied in various other forms within the scope of the following claims.

What is claimed as new, is:—

1. A sorting-machine having, in combination, feeling-means for engaging the outline of a series of articles; and means, controlled by the feeling-means, for separating the articles automatically into groups according to variations in their edge contours.

55 2. A sorting-machine having, in combination, means for testing the peripheries of a series of articles; and means, controlled by the testing-means, for separating the articles automatically into groups according to the 60 variations in the shape of their peripheries.

3. A sorting-machine having, in combination, feeling-means for engaging the marginal portions of a series of pieces of shoe-stock to detect imperfections in the shape

thereof; and means, controlled by the feeling-means, for separating the pieces automatically into groups of perfect and imperfect pieces.

4. A sorting-machine having, in combination, feeling-means for engaging the marginal portions of a series of pieces of sheet-material; and means, controlled by the feeling-means, for separating automatically, from the other pieces, those having peripheral concavities constituting substantial departures from the normal predetermined form of the pieces.

5. A sorting-machine having, in combination, feeling-means for engaging the periphery of an article formed of sheet material, and means, controlled by the feeling-means, for automatically discharging the article at one point or another according as it does or does not embody a substantial departure from a certain predetermined peripheral shape.

6. A sorting-machine having, in combination, feelers arranged to engage different parts of the surface of an article, and means, controlled by the feelers, for holding an article in position to be engaged, and for thereafter discharging the article at one point or another according as any of the feelers do or do not, when the article is in said position, occupy a position other than that which they would occupy when in engagement with an article of predetermined normal form.

7. A sorting-machine for detecting imperfections in the contour of articles having, in combination, feelers; means for moving the feelers into engagement with different parts of the periphery of an article; and mechanism, controlled by the feelers, for discharging the article at one point or another according as any of the feelers do or do not, when in engagement with the article, occupy a position other than that which they would occupy when in engagement with an article of predetermined normal contour.

8. A sorting-machine having, in combination, feelers; means for moving the feelers into engagement with different parts of the periphery of an article; and mechanism, controlled by the feelers, for discharging the article at one point or another according as any of the feelers do or do not, when in engagement with the article, project within the space occupied by an article of a predetermined normal contour.

9. A sorting-machine having, in combination, feelers arranged to engage different parts of the surface of an article; and means, controlled by the feelers and comprising a templet, for discharging the article at one point or another according as any of the feelers do or do not, when the article is in said position, occupy a position other than

- that which they would occupy when in engagement with an article of a form corresponding to that of the templet.
10. A sorting-machine having, in combination, feelers; means for moving the feelers into simultaneous engagement with different parts of the surface of an article; a templet; means for moving the templet in a space which is not occupied by any of the feelers 10 when they are in engagement with an article of normal form, but which is so occupied when the feelers engage an abnormal article; and means, connected with the templet, for discharging the article at one point 15 or another according as the templet, when moved in said space, does or does not engage a feeler.
11. A sorting-machine having, in combination, means for holding a supply of articles; feeler-mechanism comprising a plurality of feelers for engaging the edge of an article; a holder adapted to hold an article during the operation of the feeler-mechanism thereon; and means for moving 25 the holder first into position to receive an article from said supply, then into position to present the article to the feeler-mechanism, and then to a point of discharge.
12. A sorting-machine having, in combination, feelers arranged to engage different points on the peripheral edge of a heel-lift; and means for presenting a heel-lift to the feelers and for thereafter discharging the lift at one or another point according to 35 the positions occupied by the feelers when in engagement with the lift.
13. A sorting-machine having, in combination, feelers arranged to engage different points on the edge of a heel-lift; means for holding a stack of lifts; a picker adapted to 40 seize and hold a lift by engagement with the face of the lift; means for moving the picker into engagement with a lift in the stack, then into position to present the lift to the feelers, and then to a discharging position; and means for causing the picker to 45 release the lift at a point determined by the position assumed by the feelers when in engagement with the lift.
- 50 14. A sorting-machine having, in combination, means for holding a supply of lifts to be sorted; holders for stacks of lifts sorted according to their edge contour; means for detecting variations in the outlines of the lifts and means for conveying a lift, from the supply to the detecting-means and then to one or another of said holders, under the control of the detecting-means.
- 55 15. In a sorting-machine the combination of a series of feelers movable in a common plane and substantially in radial directions toward a common center; means for so moving the feelers simultaneously and yield- 60 ingly; and means for supporting a piece of sheet-material in the plane of and between the feelers during said movement whereby imperfections in the contour of the piece of material will be detected.
- 65 16. In a sorting-machine, a mechanism 70 comprising a series of detectors for testing the periphery of an article; means to support the article with its periphery free to the action of the detectors; and means to operate the detectors to detect imperfections 75 in the contour of the article, and means for discharging said article in accordance with the action of said detectors.
- 80 17. In a sorting-machine a heel-lift testing mechanism comprising a series of feelers 85 for engaging substantially the entire peripheral edge of a lift; means to support the lift to permit the free operation of the feelers on the edge thereof; a lift pattern; means to operate the feelers to compare the 90 edge contour of the lift with the edge contour of the lift pattern, and means for discharging said lift in one place or another according as it does or does not correspond to said lift pattern.
- 95 18. A sorting-machine having, in combination, a detecting device for testing pieces of sheet material; a supply device to hold blanks in stack formation; a receiving device to hold blanks in stack formation; means to adjust the supply and receiving devices to support different kinds of pieces in the same relative position in which they are operated upon by the detecting device; and a holder for carrying a piece of material from 100 the supply device to the detecting device and then delivering it to a receiving device.
- 105 19. A sorting-machine having, in combination, a detecting device for testing articles of sheet material; a supply-device to hold articles in stack formation; a receiving-device to hold articles in stack formation; and a holder to grip and take an article 110 from the supply-device, present it to the detecting-device and deliver it to a receiving-device.
- 115 20. A machine for sorting articles of sheet material having, in combination, a detecting-device; a supply-device; a plurality of receiving-devices; a plurality of holders 120 movable between said devices; means to rotate the holders to take articles from the supply-device, present them to the detecting-device and deliver them to a receiving-device; article grasping means in the holders 125 movable to and from said devices; and means under the control of said detecting-device for controlling the operation of said grasping means.
- 125 21. A machine for sorting heel lifts having, in combination, a feeling-means for engaging the periphery of an article formed of sheet material, and means controlled by the

- feeling-means for automatically discharging the article at one point or another according as it does or does not contain a projection or concavity on its peripheral edge which embodies a substantial departure from the contour of a perfect similar lift. 5
22. A sorting-machine having, in combination, a detecting-device; devices for supporting articles in stack formation; an article holder; means to move the holder into positions opposite said devices; article grasping mechanism mounted in said holder; means to move said grasping mechanism toward and from said devices; and a selective 10 cam for controlling the operation of said last named means.
23. A stacking-mechanism comprising: a receiving-device to support articles in stack formation comprising, a bottom-support, 15 and a pair of yieldingly pressed side arms to bear against the sides of the articles; a feed member for the intake end of said device; and means to operate said feed member to force blanks between the side arms.
24. A stacking-mechanism comprising; a receiving device to support articles in stack formation; means to deliver articles to said device; and a helical member operable to 20 stack articles in said device.
25. A machine of the character described having, in combination, means for operating on lifts; means to advance lifts to the operating means; a receiving device in the form of a magazine; and continuously rotating mechanism arranged to engage the marginal edge of lifts delivered from said operating means and advance them through the magazine. 30
26. A machine of the character described having, in combination, means for operating on lifts; means to advance lifts to the operating means; a receiving device in the form of a magazine; and continuously rotatable mechanism mounted at each side of the magazine to engage opposite sides of the marginal edge of lifts delivered from said operating means and advance them through the magazine. 40
27. A stacking-mechanism comprising; a receiving device to support articles in stack formation; a helical blade mounted at each side of the device; holding means timed to place an article against rear portions of the blades at the time the leading edges of the blades are separated; and means to rotate 45 the blades to force the article into said device.
28. A stacking-mechanism comprising; a receiving device to support articles in stack formation; a helical blade mounted at each side of the device; means to place an article between the convolutions of the blades; and means to rotate the blades to force the article into said device. 50
29. In a sorting-machine a feeling device comprising a series of feelers arranged in a 55 circle and movable radially toward a common center; means to support an article at their center; means to yieldingly force the feelers into engagement with the article to determine the contour of the article, and means for discharging said article at one point or another in accordance with the contour of the article acted upon. 70
30. In a sorting-machine a feeling device, comprising a series of feelers arranged in a circle and movable radially toward a common center; means to support an article at their center; means to yieldingly force the feelers into engagement with the article; means to compare the contour determined by the feelers with a pattern of a similar perfect article, and means for discharging said article at one point or another according as the contour of the article corresponds to or varies from that of the pattern. 75
31. A machine for sorting articles having, in combination, means for detecting any variation from a standard contour over a substantial area of a surface thereof, and means under the control of said detecting means for separating the articles that vary from the standard. 80
32. A machine for sorting articles having, in combination, detecting means for determining the character of a substantial area of a surface thereof and means for sorting said articles in accordance with the determinations of said detecting means. 90
33. A machine for sorting shoe stock having, in combination, testing means acting upon a surface thereof for detecting any imperfection in the contour thereof, and means for separating the perfect and imperfect stock in accordance with the detections of said testing means. 95
34. A machine for sorting shoe stock having, in combination, means for testing one of the surfaces of said stock to detect any variations thereof from a standard surface contour, and means controlled by said testing means for sorting the stock into groups according as the surface conforms to or varies from the standard contour. 100
35. A machine for sorting shoe stock having, in combination, a plurality of feelers for engaging a sufficient number of points of a surface thereof to determine its contour and means controlled by said feelers for sorting the stock in accordance with the determined contour. 110
36. A machine for sorting shoe stock having, in combination, movable feelers for engaging a surface of said stock for determining its contour, said feelers being relatively movable if the contour departs from a standard, and being relatively stationary if the contour conforms thereto, and means controlled by the relative movement of said feelers for separating the stock that departs from the standard. 115
- 120
- 125
- 130

37. A sorting machine having, in combination, means for detecting any imperfections in the margin outline of a series of articles; and automatic means controlled by said detecting means for sorting said articles into groups in accordance with the variations of their marginal outlines. 30
38. A sorting machine having, in combination, means for detecting imperfections in the shape of the marginal edges of a series of articles; and means controlled by said detecting means for separating the articles automatically into groups of perfect and imperfect articles. 10
39. A sorting machine having, in combination, a templet, means for detecting any variations in form of the articles operated upon from that of the templet, and means for sorting the articles in accordance with the action of said last means. 15
40. A sorting machine having, in combination, means for detecting the outline of a plurality of articles, a templet, means for moving the templet into operative relation with said detecting means to compare the outlines of the tested articles to that of the templet, and means for distributing said articles according as they do or do not conform to the outline of the templet. 20 25
41. A sorting machine having, in combination, means for holding a supply of articles; means for detecting imperfections in the marginal outlines of the articles; and means for receiving the articles from said supply, presenting them to said detecting means, and then discharging them in accordance with the action of said detecting means. 35
42. A sorting machine having, in combination, a detecting device; a supply-device; a receiving-device; a plurality of pickers movable between said devices; means for rotating said pickers and causing them to successively take articles from the supply-device, present them to said detecting-device 40 and deliver them to said receiving-device. 45
43. A sorting machine having, in combination, a rotatable picker mechanism comprising a plurality of radially disposed pickers; a supply-device, a testing-device, 50 and a plurality of receiving devices disposed radially around said picker mechanism; means for causing the respective pickers to successively take articles from said supply-device, present them to said testing-device 55 and discharge them into one or the other of said receiving devices. 55

ERASTUS E. WINKLEY.
